UNITED STATES PATENT OFFICE

CHARLES HOLLERITH, OF JACKSON, MICHIGAN, ASSIGNOR, BY MESNE ASSIGNMENTS, TO TERNSTEDT MANUFACTURING COMPANY, OF DETROIT, MICHIGAN, A CORPORATION OF MICHIGAN

HOOD LATCH

Application filed April 2, 1931. Serial No. 527,098.

This invention relates to latches for automobile hoods and other devices.

One of the objects of the invention is to construct a hood latch located on the inside of the hood and operated by a handle extending to the exterior through an opening in the hood with substantially constant clearance between the handle and the end of the opening in the latched and in the unlatched position.

10 Another object of the invention is to construct a handle for latches in such a way as to have the necessary strength and neat appearance but at decreased cost of production.

15 Other objects of the invention will appear in the following description, reference being had to the drawing in which:

Fig. 1 is a side view of a latch and part of the hood, the latch being partly in section.

20 Fig. 2 is a section of the latch taken on the line 2—2 of Fig. 1.

Fig. 3 is a longitudinal section of a modified form of handle of built up construction, shown by way of example as of the type 25 illustrated in Fig. 1.

Fig. 4 is a section taken on the line 4—4 of Fig. 3.

Fig. 5 is a section taken on the line 5—5 of Fig. 3.

30 Fig. 6 is a perspective view of the slide of the latch.

Fig. 7 is a perspective view of the hook member of the latch.

Fig. 8 is a perspective view of the back 35 plate.

The latch of this invention is of the general construction shown in my application filed July 8, 1930, Serial No. 466,484, though the latch itself may be varied without departing from the spirit of the invention. The latch in general consists of a hook member 1 adapted to engage a keeper 2 secured to the cowl and radiator shell at each end of the hood or to the sill. The hook member in 40 the example illustrated has a shank 3 of trough shape being open on the front and having the sides bent over at the top to form an abutment 3' against which heavy spring 4 engages at the top. The slide 5 is open at 45 both sides as shown so that the handle 9

can be pivoted between the sides and move the slide to latched and unlatched positions. There is a small back portion 7 where it unites with the finger 10. This slide has an extension or finger 10 with an abutment 11 adapted to engage the lower end of the spring 4. The hook member and the slide are enclosed in a housing 12 of rectangular trough shape, as shown in Fig. 2, the back opening of which is closed by a plate 13. The housing and back plate are fastened to the hood by appropriate screws or bolts 14. The back plate 13 has an extension 13' preferably looped out through the opening 15 in the hood and bent to return back through the opening to extend across the upper end of the housing to serve as an upper abutment for the light spring 16. This bent over portion may extend through a slot in the housing at 17. The lower end of the spring 16 rests against the 70 spring abutment 17' on the hook member 5. This construction is the one described in my copending application above referred to as far as the general features of the latch are concerned.

75 The invention in this case differs from the one in that application in the general construction of the latch handle 9 and its relation to the slide and opening in the hood. The handle 9 is pivoted at 18 at the upper 80 part of the slide 5 and has a curved portion adapted to seat in a slight depression in the bent over extension 13' of the plate 13. The hole 15 through the hood is preferably made 85 small and that part of the handle that moves in and out through this hole is made of such cross section as to have minimum clearance at 19 which will permit the handle to be inserted in assembling the latch. The handle is 90 shaped so as to keep the clearance 19 the same in the latched and unlatched positions.

95 The upper end of the handle has an extension 20 adapted to rest against the end of the projection 20', shown in Fig. 8 in the unlatched position. The purpose of this will be described later.

100 The exterior of the handle may take any shape to give a pleasing appearance and furnish a handy grip to latch and unlatch

the hood, the shape shown in Fig. 1 being suitable for the purpose.

The operation of the latch will now be briefly described:

- 5 The latch in Fig. 1 is shown in latched position with the hood closed. In this position the slide 10 is held against downward movement by position of the pin 18 directly above the point of support 19 of the handle.
- 10 It also may be held in this position by the depression 21 therein or by the point of support going past the center point. The hook 1, however, is resiliently held in engagement with the keeper 2 through the action of compression spring 4 which tends to force the hook upward. To open the hood the handle 9 will be pulled in a general upward direction and this will lower the pivot point 18 and the slide, through movement of the handle 9 which permits the spring 16 to force the slide and hook downward as a unit, the extension 20' of course being held stationary. During this action the handle 9 moves out through the opening 15 in the hood and when in lowered position the clearance at 19 will be the same as in latched position and due to the curved shape of the handle this will be of minimum amount. The preferred design is such that the handle has substantially constant cross
- 25 action when it passes through the hood opening. The handle may substantially fill the opening in all positions if desired.

The handle of a latch of the type described has heretofore been one of the main items of cost and to reduce the cost of this particular item and thus materially lower the cost of the entire latch I make the handle of stamped material, as shown in Fig. 3. In this figure I have so designed the strips as to form a latch 40 of the general type shown in Fig. 1 but it may be otherwise shaped without departing from the spirit of the invention.

The latch is formed of two strips 22, 23. The outer strip 22 is stamped with the general 45 shape shown in Fig. 3 and has the cross section shown in Figs. 4 and 5. The strip 23 is stamped to fit beneath the strip 22 and make a smooth fit therewith. This strip, however, may be of more rectangular shape, as shown in Fig. 5. At the point 24 the strips 22 and 23 are bent in opposite directions to form a more or less circular opening to receive the pin 18. The upper end 25 is bent over against the end 26 of the strip 23. These 50 parts may be welded or otherwise fastened together. This extension then may serve the same purpose as extension 20 in Fig. 1, namely to limit the downward movement of the slide.

60 The other end of strip 22 has a portion 29 bent over the end 30 of the strip 23 and similarly fastened thereto.

After each strip 23 and 22 is formed in fitting relation, they may be slid together by 65 sidewise pressure, as indicated by the arrows

E, F, in Figs. 4 and 5. The relative lengths of the two parts may also be, such that when the two halves are thus pressed together they will remain as a unit without further fastenings. After the two strips are in snug fitting relation they may be welded if desired to lock the parts in rigid relation. The two strips may also be held together by rivets or by projections forced from one piece into depressions in the other that is, by integral rivets.

A handle constructed in this way may be made of the desired shape to function as the handle 9 in Fig. 1 without any further operation, but to give the handle a neat appearance it is preferable to smooth over and polish the surface of the parts, after which the junction line between the two strips will be substantially invisible at the distance at which the operator of the latch would be positioned. The finished handle may also be given a plating of nickel, chromium or some other enduring metal or it may be otherwise finished to suit the ideas of the user.

While the opening 24 may be stamped of the desired circular contour it may in some cases be desirable to broach or ream the opening to make a smooth fit with the pin 18 that fastens the handle to the slide.

When it is desired to lift the hood, the handle 9 (Fig. 1) will be raised and the hook lowered till the projection 20 engages the extension 20'. This support taken with that afforded by the engagement of the handle with the opposite portion of the extension 13, 100 will limit the downward movement of the hook. In this position the hook is located below the guard 31 as shown in dotted lines. The handle 9 is not adapted for raising the hood and a separate bail (not shown) will 103 be used for that purpose as is usual with engine hoods. In lifting the hood by this bail the guard 31 prevents the hook from re-engaging the keeper 2. In the normal lifting operation, the hood will be pulled outwardly enough to cause the guard to clear the keeper but to prevent accidental engagement the guard is provided. This guard will prevent the hood from being lifted by the handle 9 as a pull on the handle will cause the handle to move about the fulcrum 20', compress weak spring 16 before overcoming the weight of the hood and thus will cause the hook to move above the guard and re-engage the keeper. This is not a disadvantage however, as the handles should not be used to lift the hood, one or more bails being provided for the lifting operation.

Having described my invention, what I 125 claim is:

1. In hood latches, an automobile hood having an opening, a hook member attached to the inside of the hood, a handle pivoted to said hook member at a point located above 130

40 said opening in the latched position and
adapted to move therethrough during the
latching and unlatching movements, said
handle being shaped to have substantially
5 the same clearance with the top of the opening
in the latched and unlatched positions.

45 2. In hood latches, an automobile hood having
an opening, a hook member attached to
the inside of the hood, a handle pivoted to
10 said hook member at a point located above
said opening in the latched position and
adapted to move through said opening during
the latching and unlatching movements,
15 said handle being shaped to have substantially
the same clearance with the top of the opening
in the latched and unlatched positions.

20 3. In hood latches, an automobile hood having
an opening, a hook member adapted to
slide on the inside of said hood and having
an end extending above said opening, a handle
25 pivoted to said end and adapted to
slide through said hole and a support engaging
the bottom of the lever to lift the hook
member as the handle moves through the
opening, the handle having substantially constant
30 cross section where it moves through
said opening.

35 4. In hood latches, an automobile hood having
an opening, a hook member adapted to
slide on the inside of said hood and having
an end extending above said opening, a curved
handle pivoted to said end and adapted to
40 slide through said opening, the curvature of
said handle maintaining substantially constant
clearance from the top of the opening.

45 5. In hood latches, an automobile hood having
an opening, a hook member adapted to slide
on the inside of said hood and having an end
extending above said opening, an abutment
50 below said opening, and a curved handle
having one end pivoted to said end, an
intermediate part resting on said abutment,
and the other end extending through
said opening, said handle having substantially
55 uniform cross section where it moves
through said opening.

60 6. In hood latches, an automobile hood having
an opening, a hook member adapted to slide
on the inside of said hood and having an end
extending above said opening, an abutment
65 below said opening, and a curved handle
having one end pivoted to said end, an
intermediate part resting on said abutment,
and the other end extending through
70 said opening, said handle having substantially
uniform cross section where it moves
75 through said opening.

80 6. In hood latches, an automobile hood having
an opening, a hook member adapted to slide
on the inside of said hood and having an end
extending above said opening, an abutment
85 below said opening, and a curved handle
having one end pivoted to said end, an
intermediate part resting on said abutment,
and the other end extending through
90 said opening, said handle substantially filling
95 said opening in the latched and unlatched
position.

100 7. In latches, an automobile hood having a slot, a hook member adapted to slide inside of the hood, a handle pivoted to the hook member and extending through said slot, an extension on the interior end of said handle, a keeper inside the hood and a fulcrum member engaging said extension in the unlatched position to cause an upward movement of the exterior end of the handle to raise said hook into engagement with said keeper.

105 In testimony whereof, I have signed my name to this specification this 28th day of March 1931.

110 CHARLES HOLLERITH.
